UNITED STATES PATENT OFFICE.

CONRAD LORENZ, OF NEW YORK, N.Y.

PRESS-BOARD FOR CIGAR-BOXES.

SPECIFICATION forming part of Letters Patent No. 331,510, dated December 1, 1885.

Application filed April 4, 1885. Serial No. 161,185. (No model.)

To all whom it may concern:

Be it known that I, CONRAD LORENZ, of the city, county, and State of New York, have invented certain new and useful Improvements 5 in Press-Boards for Cigar-Boxes, of which the following is a specification.

This invention has reference to an improved press-board for cigar-boxes, which can be adjusted to any length of box, so as to be conveniently used by cigar-packers in packing cigars, in place of the different sizes of press-boards heretofore in use.

The invention consists of a press-board for cigar-boxes, formed of a main piece having a 15 central transverse bottom strip, and of adjustable extension-pieces having transverse end strips which are straight at their outer and tapering at their inner sides. Between the adjustable extension-pieces of the press- 20 board and the main piece are interposed dovetailed strips of different widths, according to the length to which the press-board is to be extended. The detachable strips are stored away in a box-shaped receptacle formed by 25 the main pieces and extension-pieces, and inclosed by a hinged cover that is attached by locking devices to the main piece.

In the accompanying drawings, Figure 1 represents a vertical longitudinal section of a 30 cigar-box, with my improved press-board shown in position in the box. Fig. 2 is a side elevation of my improved press-board, shown partly extended. Fig. 3 is a vertical longitudinal section on line $x-x$, Fig. 4; Fig. 35 4, a plan with the hinged cover in open position; and Fig. 5 is a vertical transverse section on line $y-y$, Fig. 3.

Similar letters of reference indicate corresponding parts.

Referring to the drawings, A represents the 40 main piece and B B the extension-pieces of my improved press-board for cigar-boxes. The main piece A is provided at its under side with a fixed central transverse strip, a , that is beveled at both sides and provided with a downwardly-extending tapering piece, a' , which latter separates the cigar-bundles, as shown in Fig. 1. The extension-pieces B B are guided by shorter top pieces, B' B', along 45 beveled side strips, b b , at the top, and central 50 grooves along central dovetail guide-rails, b' ,

at the under side of the main piece A. The extension-pieces B B are provided with downwardly-projecting transverse end strips, d d , which are made tapering at their inner sides 55 and straight at their outer sides, so as to fit snugly into the cigar-boxes. The top pieces, B', of the extension-pieces B B are connected by a strong spiral spring, C, which is attached to eyes of the top pieces, B'. The inner edges 60 of the extension-pieces B B are made beveled, for the purpose of inserting between them and the beveled sides of the strip a interchangeable strips D D of dovetail shape and different widths, according to the length to which 65 the press-board is to be adjusted. By providing a number of dovetailed strips D D the extension-pieces B B can be adjusted to any length of cigar-box, from the shortest to the longest, by simply pulling the extension- 70 pieces in outward direction against the tension of the spring C and inserting strips D D of the required thickness between the inner ends of the extension-pieces and the transverse bottom strip, a . 75

After use the detachable strips D D are stored away between the upper parts, B' B', of the extensions B B and the side strips, b b , of the main piece A, and then covered by a hinged cover, E, which is locked to the main 80 piece A by a hook and eye, e e' , or other fastening device. When the press-board has been adjusted to the proper length of cigar-box and placed on the cigar-bundles in the same, as shown in Fig. 1, the box is placed 85 with the press-board in the usual manner into a press, and the press-board pressed down on the cigars until the required degree of compression is obtained. The press-board is then removed and placed on the next box, and so on. 90

As the width of the press-board remains the same for all sizes of boxes, the press-board requires only to be adjusted in longitudinal direction, as the pressure has to be exerted on the middle thicker portion of the cigar-bundles, so as to reduce them sufficiently in size to fit into the box. 95

Having thus described my invention, I claim as new and desire to secure by Letters Patent—

1. The combination of a main piece having a central transverse bottom strip, adjustable extension-pieces having end strips, and 100

- interchangeable strips interposed between the main piece and extension-pieces to regulate the length of the press-board, substantially as set forth.
- 5 2. The combination of a main piece having a transverse central bottom strip, adjustable extension-pieces guided on the main piece and having transverse end strips and a spiral spring connecting the extension-pieces, substantially as set forth.
- 10 3. The combination of a main piece having a central transverse bottom strip, adjustable extension-pieces guided on said main piece, and provided with transverse end strips bevelled at their inner sides, a spiral spring connecting the inner ends of the extension-pieces, and interchangeable strips interposed between the main and extension pieces, substantially as set forth.
- 15 4. The combination of a main piece, adjustable extension-pieces guided on the main piece, interchangeable strips interposed be-
- 20
- tween the main and extension pieces, and a cover hinged to the main piece and inclosing a storage-space between the main and extension pieces for the interchangeable strips, substantially as set forth.
- 25 5. The combination of a main piece, A, having guide-strips $b b'$, and a central transverse bottom-strip, $a a'$, adjustable extension-pieces B B', having top pieces, $B' B'$, and end strips, $d d'$, spiral spring C, connecting the top pieces, $B' B'$, and interchangeable strips D D', that are interposed between the transverse strip a and the extension-pieces B B', substantially as set forth.
- 30
- 35
- In testimony that I claim the foregoing as my invention I have signed my name in presence of two subscribing witnesses.

CONRAD LORENZ.
